UNITED STATES PATENT OFFICE.

LOUIS E. MACKEY AND FRANK W. ORMISTON, OF DETROIT, MICHIGAN.

WINDING AND REWINDING MECHANISM.

1,309,256.

Specification of Letters Patent.

Patented July 8, 1919.

Application filed August 5, 1918. Serial No. 248,276.

To all whom it may concern:

Be it known that we, LOUIS E. MACKEY and FRANK W. ORMISTON, citizens of the United States, residing at Detroit, in the 5 county of Wayne and State of Michigan, have invented a new and useful Winding and Rewinding Mechanism, of which the following is a specification.

This invention relates to winding and re- 10 winding mechanisms comprising a web or other flexible member adapted to be actuated from one to the other of a pair of reels, such as are employed in street indicators and the like.

15 It is the object of the invention to provide for alternatively establishing a forward and reverse drive connection with the reels to provide means for retarding the rotation of the reel from which the web is being unwound, and for yieldably restraining rotation of both reels to a lesser degree when neither one is being driven, and to provide a common means for selectively controlling the drive to the reels, the application 20 of the braking or retarding means, and for simultaneously making and breaking an electric circuit for controlling a motor employed to actuate the reels.

In attaining this object the invention con- 30 templates employing a gear slideable upon a motor shaft to engage either of two gears for actuating the respective reels and a slide bar by which movement of said sliding gear is controlled, which bar is adapted to bridge 35 spaced contacts in the motor circuit, and which furthermore carries brake members respectively co-acting with drums upon the shafts of the respective reels.

A preferred embodiment of the invention 40 is disclosed in the accompanying drawings, wherein,

Figure 1 is an end elevation of a street indicator which is provided with the herein-described winding and rewinding mechanism.

Fig. 2 is a transverse vertical sectional view of the indicator.

Fig. 3 is a front view of the indicator omitting the front wall thereof, the actuating motor and its circuit being diagrammatically shown.

In these views the reference character 1 designates a casing having a sight window 2 provided in its front wall. A web 3 is 55 adapted to travel within the casing in front of said window, passing over a pair of guide

rollers 4 disposed respectively above and below said window and having its end portions respectively wound upon reels 5 and 6. The shafts 7 of said reels project exteriorly of the casing 1 at one end thereof and respectively carry gears 8 which are relatively offset, said gears being alternatively engageable by a pinion 9 slidably mounted intermediate the same upon a shaft 60 10 having a journal bearing in the wall of the casing to which said gears are adjacent. To shift the pinion 9 on the shaft 10 so as to vary its engagement with the gears 8, a pair of bell cranks 11 are pivoted adjacent the 65 pinion, corresponding arms thereof being engaged in an annular groove formed in a hub 12 upon the pinion, and the other arms of said bell-cranks being extended into the casing through an opening in the end wall 70 75 thereof. Within the casing, the bell-cranks are pivotally connected to a vertical bar 13 slidably mounted in a bearing 14 at its upper end and in the casing bottom adjacent its lower end, said bar being extended beneath the casing and terminating in a handle by which it may be actuated.

For actuating the shaft 10, a motor 15 is provided, said motor being in a circuit 16 including contacts 17, between which said 85 circuit is broken when the bar 13 is in its intermediate position (corresponding to the neutral position of the pinion 9), while in either the raised or lowered position of the bar, a contact plate 18 carried by said bar 90 bridges between the contacts 17 so as to close the motor circuit.

The bar 13 carries a pair of duplicate 95 brake members 19, each comprising a pair of resilient bowed prongs 20 and 21, said members being engageable with brake drums 22 upon the shafts 7. The prongs 20 and 21 are relatively offset in order that the prongs 20 of both members 19 may engage their respective drums 22 when the bar 13 100 is in intermediate position, while movement of the bar in either direction increases the braking pressure exerted by the prong 20 upon the reel toward which the bar is shifted and further brings the corresponding prong 105 21 into braking position. At the same time the reel from which the bar is shifted is relieved of extreme braking pressure owing to disengagement of the corresponding prong 20 from its drum. Since shifting of the bar 110 to either limiting position effects establishment of a drive connection to the reel from

which the bar moves away, it will be evident from the foregoing that when the drive is cut off from both reels, a moderate braking pressure is applied to both reels tending 5 to immediately halt travel of the web, while a somewhat greater braking pressure is applied to either reel when the companion reel is functioning to drive the web, the effect being to maintain the web constantly 10 taut, and to prevent momentum of the reels effecting any appreciable travel of the web after the drive has been cut off.

It will further be evident from the preceding description that the bar 13 exercises 15 a triple function, since it selectively controls establishment of a drive connection to the reels through the pinion 9 and gears 8, makes and breaks the motor circuit according as the gears are in driving or neutral position, and checks rotation of the reel from which the web is to be unwound or of both reels when the bar is in its intermediate position corresponding to the neutral position of the driving gears.

20 While the disclosed winding and rewinding mechanism is particularly designed for application to a street indicator for railway vehicles, it is evident that it may be applied to a large number of other useful purposes.

25 What we claim is:

1. A winding and rewinding mechanism comprising a pair of reels, a web extending

35 between the reels and having its end portions respectively wound thereon, an electric motor and circuit therefor, mechanism for alternatively driving the reels from the motor, said mechanism having a neutral position, mechanism for alternatively checking rotation of the reels, and a common means for shifting the drive of the motor from one to the other of said reels, for 40 shifting the application of the checking mechanism from one reel to the other and for closing the motor circuit when the drive 45 to either reel is established and breaking said circuit when the driving mechanism is in neutral position.

2. A winding and rewinding mechanism 50 comprising a pair of reels, a web extending between the reels and having its end portions respectively wound thereon, an electric motor and circuit therefor, mechanism for alternatively driving the reels from the motor, and a common means for shifting 55 the drive of said motor from one of said reels to the other and for closing the motor circuit when the drive to either reel is established and for breaking said circuit when the driving mechanism is in neutral 60 position.

In testimony whereof we sign this specification.

LOUIS E. MACKEY.
FRANK W. ORMISTON.
